MECHANISM FOR STACKING CARTONS AND
THE LIKE

Michael Paridon, Barberton, Ohio, assignor to
The Diamond Match Company, Baltimore,
Md., a corporation of Maryland

Application October 30, 1931. Serial No. 571,949

6 Claims. (Cl. 93—49)

This invention relates to machines for stacking open-mouth boxes, such as cartons or trays, having collapsible sides and ends, and it has for its object to provide a simple and efficient construction and organization of mechanism whereby such boxes are successively flattened and stacked to occupy comparatively small compass for convenience of packing and transportation.

The invention has been especially, though not exclusively, designed for use in connection with or as an attachment to machines for making shallow collapsible cartons whereby the said cartons as rapidly as they are discharged from the machine are intercepted and compactly assembled.

The invention, broadly considered, comprises the combination with means for supplying collapsible boxes, of simple, durable and efficient means for flattening the boxes and arranging them in stacked relation.

More specifically, the invention comprises the combination with a carrier for supporting a succession of collapsible boxes, bottoms downward, and feeding them successively to a point of discharge, and a vertically-reciprocating plunger for discharging the boxes successively from the carrier, of a box receiver under the path of the plunger, means for temporarily supporting each succeeding box at the mouth of the receiver, and means for folding the collapsible end walls of the box in a manner to bend the side walls outwardly in the same plane as the bottom of the box, and at the same time depressing the flattened box into the receiver.

The invention also comprises various features of construction and combinations of parts which will be hereinafter described; the scope of the invention being expressed in the appended claims.

In the drawings—

Figure 1 is a front elevation, partly in section, of box stacking mechanism embodying the preferred form of my invention, the mechanism being represented as associated with the discharge portion of a box making machine.

Fig. 2 is a transverse vertical section, as on the line 2—2 of Fig. 1, showing the parts in their relative positions preparatory to the collapsing or flattening of the box by the folding or ironing members.

Fig. 3 is a similar section, showing the relative positions of the parts upon the completion of the flattening operation.

Fig. 4 is a horizontal section, as on the line 4—4 of Fig. 2.

Fig. 5 is a perspective view of a collapsible box or carton.

Fig. 6 is a similar view of said box or carton as collapsed or flattened.

Referring to the drawings, 10 designates several of the open former links of the endless chain of a well-known type of box-making machine, which links are intermittently impelled in the usual manner to the path of a vertically-reciprocating ejector 11, whereby in each dwell of the chain a collapsible box (B) is discharged from one of the links through an opening 12 in a table 13 which is supported by a standard 14 on the frame structure.

The form of box herein illustrated comprises a bottom a, end walls b and side walls c, the latter having therein adjacent the ends diagonal scores or creases d which enable the box to be collapsed or flattened by the application of inward pressure to the respective end walls.

The form of ejector illustrated is similar to that described in Letters Patent of the United States No. 1,287,088 dated December 10, 1918, that is to say, it comprises a yielding frame of inverted V-form supported by a vertically-reciprocative cross-head 15 which is mounted on vertical guide posts 16 on the table. This cross-head is connected by means of a link 17 to one arm of a rock-lever 18 which is fulcrumed on a standard 19 on the supporting frame. The other arm of the lever is connected by means of a link 20 with one arm of a lower rock-lever 21 which is also fulcrumed on the standard 19; the other arm of the lever 21 having a roll 22 operatively fitted in the run of a suitably-disposed face cam 23. This cam is fast on a drive shaft 24 having its bearings in suitable standards, including the standard 14 on the main frame, whereby during the operation of said shaft the cam in its rotation effects, through the described lever and link connections, the timely reciprocation of the ejector in respect to each succeeding link of the box chain.

As each box is discharged through the opening 12 of the table 13 the box is temporarily supported at the mouth of a guide chute 25 depending from the table, which box is collapsed or flattened and then entered in the chute, as will presently appear. This chute is of appropriate internal form and dimensions for the reception and guidance therein of each succeeding flattened box, so that when the articles are discharged from the chute they are stacked in orderly condition for convenience of packing and transportation. The chute thus constitutes a receiving and stacking element for the flattened boxes.

At the top of the chute 25 are fingers 26 which are movable into and from the paths of the end portions of each succeeding box discharged from the chain 10, the walls of the chute having suitable openings 27 for the passage of the fingers. These fingers when in inward position intercept and support the box as it is discharged by the plunger 11, and when in outward position they permit the descent of the flattened box in the chute. In the present instance the fingers are formed on the upper ends of upstanding arms 28 having at their lower ends sleeves 29 which are fulcrumed on shafts 30 fixed to brackets 31 on the bed 32 of the machine. Fast on the sleeves 29 are upstanding arms 33 having at their upper ends rolls 34 which are normally maintained in operative contact with a cam 35 by means of suitably-disposed springs 36. This cam is fast on a shaft 37 which has its bearing in the standard 14 and is driven from the main shaft 24 through meshing gear wheels 38 on the respective shafts. The contour of the cam 35 is such that the arms 33 and their companion arms 28 are simultaneously actuated to effect the inward and outward movement of the fingers 26 in timed relation to the operation of the box ejector.

Two oppositely-disposed folders are reciprocative in longitudinal paths intersecting the vertical planes of the respective end walls of the box 30 overlying the chute, whereby such ends and the creased corners of the sides of the box are pressed down in a manner to collapse or flatten the box, that is, the ends are folded inwardly and downwardly and the sides are bent outwardly in the same plane as the bottom of the box. (See Fig. 6). In the present instance each of the folders comprises an elongated body plate 39 having upstanding perforated ears 40 which are slidably fitted on a guide rod 41 projecting from the table 13, and having also spaced depending ironing members 42 of substantial length which are curved or beveled at their nose portions 43 so as to bear smoothly against and iron down the opposing end wall of the box. The folders are connected by means of links 44 to the upper ends of upstanding arms 45 having at their lower ends sleeves 46 which are fulcrumed on shafts 47 fixed to brackets 48 on the bed of the machine. Fast on the sleeves 46 are upstanding arms 480, the upper ends of which are connected by links 49 with upstanding arms 50 pivotally supported on the respective shafts 30. The arms 50 are equipped with rolls 51 which are normally maintained in operative contact with a cam 52 fast on the shaft 37 by means of suitably-disposed springs 53, the contour of the cam 52 being such that the arms 50 and their associated arms 45, 480 are simultaneously actuated to effect the requisite inward and outward movements of the folders in timed relation to the operations of the fingers 26 and the box ejector 11.

In the construction illustrated the ratio of the gearing between the shafts 24 and 37 is such that the shaft 37 which carries the cams 35 and 52 makes one rotation during two rotations of the shaft 24 which carries the cam 23; the contour of the latter cam is such that the ejector is lowered and raised during one-half rotation of the shaft 24 but is at rest during the remainder of the rotation, and the relative contours of the two cams 35, 52 are such that in each rotation of the shaft 37, while the ejector is at rest in raised position, the arms for actuating the fingers 26 and folders 42, respectively, are reciprocated in opposite directions to each other.

In the relative positions of the parts shown in Fig. 2 the fingers 26 are in inward position, a box (B) is seated on the fingers, the ejector 11 is up and the folders 42 are outward. In a quarter rotation of the shaft 37 and its cams 35 and 52 the parts are caused to assume the relative positions shown in Fig. 3, that is to say, the fingers 26 are gradually moved outward away from the ends of the box, and coincidentally the folders 42 are moved inward, the lower acting surfaces of such folders thus pressing the opposing end walls b of the box inward and downward and the scored or creased side walls c outward and downward and at the same time forcing the flattened box down in the mouth of the chute. In the next quarter turn of the shaft 37 the folders 42 are moved outward, the fingers 26 are moved inward upon the ends of the previously flattened box, and the ejector is moved downward and upward, another box being positioned on the fingers by the descending ejector as seen in Fig. 2. In the next succeeding two quarter rotations of the shaft 37 the operations just described are repeated, and so on the succeeding boxes are discharged from the box making machine, flattened, and entered in the chute. The assembled boxes progress to the bottom or discharge end of the chute from which predetermined quantities can be removed for packing or other purpose.

It is to be understood that my invention is not limited to the structural features herein illustrated, as the mechanism may be variously modified within the principle of the invention and the scope of the appended claims.

I claim—

1. The combination with means for supplying open mouth boxes each having a bottom and collapsible wall members, of reciprocative folding members movable toward and from each other across the bottom of each succeeding box 115 interposed therebetween and operative to fold and iron the opposing end walls upon the bottom and at the same time effect the outward bending of the respective side walls of the box, and a receiving element into which the flattened boxes 120 are successively delivered.

2. The combination with means for supplying open mouth boxes each having a bottom and collapsible wall members, of means for supporting the bottom of each succeeding box, at the end 125 walls thereof, reciprocative folding members movable toward and from each other across the bottom of each succeeding box interposed therebetween and operative to fold and iron the opposing end walls upon the bottom and at the same 130 time effect the outward bending of the respective side walls of the box, and means for actuating the supporting means and folding members in timed relation to each other.

3. The combination with means for supplying boxes each having a bottom and collapsible wall members, of a vertically disposed box-receiving element, means for supporting each succeeding box in horizontal position at the mouth of the receiving element, means including oppositely reciprocative ironing members for folding the collapsible members of the box and at the same time depressing the box into the receiving element, and means for actuating the supporting and folding means in timed relation to each other.

4. The combination with means for supplying boxes each having a bottom and collapsible wall members, of a box-receiving element, means including reciprocative fingers for supporting a box 150

- at the mouth of the receiving element, said fingers movable under and from the bottom of the box at the end walls thereof, means including a pair of oppositely acting ironing members for simultaneously folding the end walls and effecting the outward bending of the respective side walls of the box, and means for actuating the said fingers and ironing means in timed relation to each other.
- 10 5. The combination with means for supplying boxes each having a bottom and collapsible wall members, of a box-receiving element, means including reciprocative fingers for supporting a box at the mouth of the receiving element, means including a pair of reciprocative depending ironing members for folding the collapsible members of the box and at the same time depressing the box into the receiving element, and means for reciprocating the said fingers and ironing members in timed relation to each other.
